UNITED STATES PATENT OFFICE

WILLARD D. ROBERSON, OF NEW YORK, N. Y., ASSIGNOR TO HESS, GOLDSMITH & CO., INC.,
OF NEW YORK, N. Y., A CORPORATION OF DELAWARE

DESIGN FOR A TEXTILE FABRIC

Application filed November 2, 1932. Serial No. 45,700. Term of patent 3½ years.

To all whom it may concern:

Be it known that I, WILLARD D. ROBERSON, a citizen of the United States, residing at 1441 Broadway, New York city, in the county of New York, State of New York, have invented a new, original, and ornamental Design for Textile Fabric, of which the following is a specification, reference being had to the accompanying drawing, forming part thereof.

The figure is a plan view of a section of textile fabric, showing my new design, which is intended to be carried forward or repeated ad libitum.

The indicating arrows, which form no part of the design, enclose a complete unit of the design, which is repeated vertically by matching the top of the unit with the bottom for the full width of the unit, and is repeated horizontally by matching the elements of the lower half of the left hand side of the unit with those of the upper half of the right hand side.

I claim:

The ornamental design for a textile fabric, as shown and described.

WILLARD D. ROBERSON.
